UNITED STATES PATENT OFFICE.

DANIEL L. BRAINE, OF NEW YORK, N. Y., ASSIGNOR TO COMPOSITE TIE-PLATE CORPORATION, OF NEW YORK, N. Y., A CORPORATION OF NEW YORK.

TIE-PLATE.

1,076,811.

Specification of Letters Patent.

Patented Oct. 28, 1913.

Application filed October 24, 1912. Serial No. 727,535.

To all whom it may concern:

Be it known that I, DANIEL L. BRAINE, a citizen of the United States, residing at New York, in the county of New York and State 5 of New York, have invented certain new and useful Improvements in Tie-Plates, of which the following is a specification.

This invention relates to improvements in railway rail-supporting devices.

10 The object of this invention is to provide a rail-supporting device, or tie-plate, as it is most commonly termed by those skilled in the art, which will serve to support the track rail in such manner as not to interrupt the wave motions thereof caused by passing of trains.

Another object is to provide an economical means of support for a rail which may be easily replaced without the necessity of 20 removing the rail or interfering with its position.

Still another object is to provide a rail-supporting means adapted to be carried by the conventional form of any tie now in use, 25 if so desired, in such a manner that the tie is to all intents and purposes preserved from the cutting or crushing effect of the rail, and so that if found desirable the tie proper 30 may be embedded in the road ballast to the greatest possible extent, thereby increasing the stability of the entire tracking system without interfering with the support of the rails, and providing for an easier riding track, as well as minimizing the displacing 35 of the ties and grinding of track when used as part of an electric railway signal system.

Other objects will be made apparent in connection with the accompanying drawings, in which—

40 Figure 1 is a side elevation of my improved device showing the rail in cross section. Fig. 2 is a plan view of the assembled device. Fig. 3 is a side elevation, looking in a direction at right angles to Fig. 1 and 45 with the fastening means removed. Fig. 4 is a detail cross section taken on the line 4—4 of Fig. 2, showing a cut spike in elevation. Fig. 5 is a view similar to Fig. 4 taken along the line 5—5 of Fig. 2, showing 50 the screw spike in elevation. Fig. 6 is a perspective view of the device proper; and

Fig. 7 is a perspective view of the wood block.

Like numerals refer to like elements throughout the drawings, in which— 55

10 designates a cross tie of the form usually used in track construction, and 16 is a rail, also of conventional construction. This rail is provided with the usual flanged base 17, having lateral edges 17^a, as shown 60 in Fig. 1 of the drawings.

My invention comprises a block or pad 18, preferably formed of a hard wood, such as beech, etc., which is preferably provided with spiking apertures 18^a—see Fig. 7. 65 Mounted on this block is a metal frame 19, having a pair of downwardly extending sides 20 adapted to embrace and closely fit the sides of the block 18, as shown in Figs. 3 and 6. These sides of the frame 19 preferably terminate short of the bottom of the block. Extending between the sides of the frame 19 are the top portions or cross pieces 70 21 and 21^a, the latter being preferably of greater width than the former, for a purpose to be hereinafter described. These top portions are spaced apart a suitable distance to accommodate the base of the rail. 75

It is to be noted that in referring to the width of the top portions 21 and 21^a, the 80 distance from the side adjacent the rail base to the opposite parallel side is intended. The inner sides of the cross pieces are preferably so located as to contact with the lateral edges 17^a of the flanged base of the rail, 85 as shown in Fig. 1. The portions of the sides 20 of the metal frame extending between the cross pieces 21 and 21^a are preferably constructed so as to terminate short of the top of the block 18 directly under the 90 rail base, thereby obviating any contact between the base of the rail and the sides of the metal frame.

Each of the cross pieces 21 and 21^a is 95 preferably provided with a circular spiking aperture 14 and a rectangular cut spike aperture 15, both of said apertures in each top portion being diagonally opposed to the similar aperture in the other cross piece, as shown in Fig. 6. Partially surrounding the 100 circular spiking aperture 14 is a raised shoulder 22, having a dished-out portion 23

immediately surrounding the aperture. These spiking apertures are so constructed as to partially open into the space between the cross pieces 21 and 21^a, the inner periphery of the aperture embracing sufficient of the screw spike to prevent lateral movement thereof and to firmly hold the spike in a vertical position and away from immediate contact with the rail-base.

10 Partially surrounding the cut-spike apertures 15 are raised shoulders 27, slightly inclined toward the center of the metal frame, as indicated at 27^a. These spiking apertures are provided with notched-out portions 28 at 15 the rear of said side aperture to position the spike and hold it away from the rail-base. A flange or shoulder 24 extends along the inner side of each of said top portions. A layer of felt *a* is used and placed between 20 the wood block and tie to absorb moisture and minimize danger of same rotting wood block, as well as to form a good seat therefor.

When the device proper is assembled and 25 set in place, the block 18 is inserted in the frame 19 and both placed in the desired position on the felt layer or the tie, or other supporting means, 10, the apertures 18^a of the wood block being located beneath the respective apertures 14 and 15 in the frame. Cut 30 spikes 30 may then be driven through the apertures 15 and 18^a into the tie 10, as shown in Fig. 4. The spike 30 is provided with a head 31 and with outwardly extending portions 29 below said head which are fitted into and engaged by the notches 28 to prevent 35 lateral movement of said spike after being driven to position.

The shoulder 27 furnishes a limit for the 40 downward movement of the spike 30, the top of the inclined portions 27^a of said shoulder furnishing a seat or restraining means for the under portion of the head 31 of the spike, thus securing the said parts firmly in 45 position. The notches 28, as already set forth, act to retain and hold the head 31 of the spike slightly out of mediate contact with the base of the rail. The screw spikes 25 may be forced into engaging position 50 through the spiking apertures 14 and corresponding apertures 18^a in the block 18. These screw spikes are provided with heads 26, the under surfaces of which are adapted to fit the dished-out portions 23 of the surrounding shoulder 22, so as to retain and hold the head 26 of the spike 25 slightly out 55 of contact with the base of the rail.

By so locating the cut and screw pikes, it minimizes the danger of splitting the wood 60 block, and it will be apparent that the slight wave motions, both vertical and longitudinal, of the rail may be uninterrupted without tending to withdraw the spikes by the rail-base, as is now found to be present 65 in ordinary track constructions. The metal

frame serves also to prevent the wood block from splitting, and it will be apparent that any side thrust—transmitted from the flange of the rail—will be distributed by the frame to both sets of spikes. Furthermore, the 70 shoulders located in the back of the cut and screw spikes will serve to prevent backward bending of the spike heads, should the rail-base be forced against them.

It will be seen that the wood block furnishes the main contacting as well as the cushioning support for the track rail, and inasmuch as this block may be of any desired length, the friction present between the base of the block and the top of the tie 75 10 may be increased by increasing the length of said block in the desired direction. Since no downward thrust is imparted to the metal frame, and since this metal frame is entirely out of contact with the tie 10, it will be apparent that cutting and crushing of the tie itself will be practically obviated. The 80 wearing effect, etc.,—due to the support of the rail—will be sustained by the wood block 85 18. It is obvious that this block when worn 90 out may be readily replaced or renewed by removing the spikes, without affecting the position of the tie or necessitating tampering with the road ballasting. By diagonally opposing the screw and cut spike holes 95 the position of the metal frame may be reversed, or the position of the wooden block may be reversed with respect to the metal frame, thus utilizing the frame drive spike holes for the screw spikes, and vice versa. 100

It is to be noted that I have constructed one top portion 21^a of greater width than the top portion 21. This top portion is adapted to be located at the outer side of the rail, where the greater thrust naturally occurs, and where the greatest amount of frictional resistance is required. 105

While I have described and shown my invention with more or less particularity, I do not wish to be unduly restricted to such description and showing beyond the scope of 110 the appended claims.

What I claim is:

1. In a device of the class described, the combination of a pad or cushioning member to form the direct support for a railway rail, an embracing metal frame provided with side members fitting the sides of the pad member and below its upper surface, and upper cross members tying the side members together and fitting the edges of the flanged base of the rail each provided with shouldered perforations for the railway spikes of the combination and arranged to hold them away from contacting the rail 120 base.

2. In a device of the class described, the combination of a pad member to form the direct support for a railway rail, an embracing iron frame provided with side mem- 125 130

bers fitting the sides of the pad member and below its upper surface and two upper cross members tying the side members together provided and fitting the edges of the flanged 5 base of the railway rail each provided with a squared spike and a circular screw perforation having shoulders to keep the cut spike and screw spike from contacting the lateral edges and upper surface of the 10 flanged base of the rail.

3. In a device of the class described, the combination of a pad or cushioning member to form the direct support for a railway rail, an embracing metal frame provided 15 with side members fitting the sides of the pad member and below its upper surface, and upper cross members tying the side members together and fitting the edges of the flanged base of the rail each provided 20 with shouldered perforations for the railway spikes of the combination.

4. In a device of the class described, a frame member and a block cushioning member, the former member resting on 25 and partially embracing the block member and provided with top cross members, said top members being spaced apart so that the inner edges thereof closely fit the base of a rail carried on said block, 30 one of said top portions being of substantially greater width than the opposite top portion.

5. In a device of the class described, a frame member and a block cushioning member, the frame member resting on and partially embracing said block member and provided with top cross members, said top 35 members being spaced apart so that the inner edges thereof closely fit the base of a rail carried on said block, each of said top portions being provided with a pair of spiking apertures, one of said apertures being circular in contour, and a raised shoulder surrounding said circular aperture.

40 45 6. In a device of the class described, a frame member and a block cushioning member, the frame member resting on and partially embracing said block member and provided with top cross members, said top 50 members being spaced apart so that the inner edges thereof closely fit the base of a rail

carried on said block, said top portions being provided with a cut spike aperture surrounded by a raised shoulder.

7. In a device of the class described, a 55 frame member and a block cushioning member, the frame member resting on and partially embracing said block member and provided with top cross members, said top members being spaced apart so that the inner 60 edges thereof closely fit the base of a rail carried on said block, each of said top portions having a cut spike aperture surrounded by a raised shoulder, the periphery of said aperture being notched. 65

8. In a device of the class described, a frame member and a block cushioning member, the frame member resting on and partially embracing said block member and having top cross members, said top members 70 being spaced apart so that the inner edges thereof closely fit the base of a rail carried on said block, said top portions being each provided with a cut spike aperture surrounded by a raised shoulder, said shoulder 75 being inclined toward the center of said frame.

9. In a device of the class described, a frame member and a block cushioning member, the frame member resting on and partially embracing said block member and having top cross members, said top cross members being spaced apart so that the inner 80 edges thereof closely fit the base of a rail carried on said block, the inner edge of each 85 of said cross members having an upwardly extending flange.

10. In combination, a wood cushioning block, a metal frame resting on and partially embracing said block and having a 90 spiking aperture, a spike extending through said spiking aperture to secure said block and frame to a supporting means, and means adjacent said spiking aperture to prevent bending or turning of said spike. 95

In testimony whereof, I have subscribed my name.

DANIEL L. BRAINE.
